DESIGN FOR A DECORATIVE WALL PLAQUE OR ANALOGOUS ARTICLE

Arthur A. Nudell, Chicago, Ill.

Application February 9, 1939, Serial No. 82,891

Term of patent 3½ years

To all whom it may concern:

Be it known that I, Arthur A. Nudell, a citizen of the United States, residing at Chicago, in the county of Cook and State of Illinois, have invented a new, original, and ornamental Design for Decorative Wall Plaque or Analogous Article, of which the following is a specification, reference being made to the accompanying drawing, forming a part thereof.

On the drawing,

Fig. 1 is a front elevational view of a decorative wall plaque illustrating my new design.

Fig. 2 is a side view thereof.

I claim:

The ornamental design for a decorative wall plaque or analogous article, as shown.

ARTHUR A. NUDELL.
